[57] CLAIM

The ornamental design for a storage unit for electrical hardware items, as shown and described.

DESCRIPTION

FIG. 1 is a top, front, and right side perspective view of a storage unit for electrical hardware items showing our new design;

FIG. 2 is an enlarged right side elevational view thereof;

FIG. 3 is an enlarged front elevational view thereof;

FIG. 4 is an enlarged left side elevational view thereof;

FIG. 5 is an enlarged top plan view thereof;

FIG. 6 is an enlarged bottom plan view thereof; and,

FIG. 7 is an enlarged rear elevational view thereof.
